UNITED STATES PATENT OFFICE.

FRANK B. JOHNSON, OF FLATBUSH, ASSIGNOR TO THE NATIONAL FINANCE COMPANY, OF BROOKLYN, NEW YORK.

TREADLE.

SPECIFICATION forming part of Letters Patent No. 424,444, dated March 25, 1890.

Application filed December 11, 1889. Serial No. 333,328. (No model.)

To all whom it may concern:

Be it known that I, FRANK B. JOHNSON, a citizen of the United States, residing at Windsor Terrace, in the town of Flatbush, in the county of Kings and State of New York, have invented a new and useful Improvement in Treadles, of which the following is a specification.

The object of the present invention is to provide a simple, economical, and efficient spring-supported pivotally-acting treadle for machines driven by foot-power, whereby the treadle can be rocked or oscillated upon its pivots to give the desired vertical throw to the pitman attached thereto without compressing the springs to their injury or causing discomfort or fatigue to the operator, and at the same time the springs will be compressed and will expand sufficiently under the weight of the feet and limbs of the operator and the movements and force naturally applied to oscillate the treadle to reduce and distribute shocks and strains attending the operation of such machines, and whereby horizontal and vertical movements to and from the operator are given to the treadle, which, by changing the angle of the treadle and the pitman, greatly assist the easy and effective operation of the machine.

30 My invention is illustrated in the accompanying drawings, in which—

Figure 1 is a plan view of a treadle and supporting-springs containing my invention and their attachments. Fig. 2 is a sectional view 35 through the line $x x$ of Fig. 1, showing, also, the driving-wheel of a machine. Fig. 3 is a plan and sectional view of a modified form of treadle-supporting springs.

In the drawings, A represents a treadle of 40 substantially the usual construction for foot-power machines.

B B are coiled springs located at or near the ends of treadle A and having one of their ends loosely attached to the treadle, so that 45 it is pivoted to rock or oscillate upon these points of attachment. The springs B B are preferably made of steel wire properly tempered and spirally coiled, and they are conveniently attached to the treadle A by shoul- 50 dered screws C, inserted through eyes formed at the end of each spring and screwed into

the treadle, the eyes of the springs being held loosely between the head of the screws and the treadle, thus pivoting the treadle upon the springs. The pivotal points are preferably 55 at about one-third the width of the treadle, the lesser part of the treadle as divided by the line of oscillation being toward the operator. The opposite ends of the springs B B are fixed to the frame of the machine, conveniently to 60 a rigid rod or bar D, connecting the standards thereof. This union is conveniently made by inserting the ends of the springs into holes bored through the rod D and fixing them in position by riveting or bending, or by any 65 other desirable means. The rod D is rigidly attached to the frame of the machine.

The treadle A, as will be observed, is supported wholly by the springs B B and is free to move in any direction in which it is carried by the action of the springs, either vertically or horizontally—that is, to and from the operator. It is especially noticed that the attachments of the springs to the treadle are at a considerable distance from and in a 70 lateral direction to the axes of the springs, or, in other words, they are outside of a vertical plane passing through the axes of the springs, and that consequently whenever the springs are contracted or expanded a 75 lateral movement of the treadle A will be produced. The treadle, through its attachment to the ends of the springs, will be moved in a horizontal direction, or to or from the operator. For instance, when the springs are compressed the 80 points of attachment and oscillation are lowered, and the treadle A and the lower end of the pitman attached thereto will be moved horizontally or laterally by reason of the swinging of the ends of the springs attached to the treadle on their axes as centers while 85 the springs are being compressed. When the pressure is removed or relaxed, as is the case with each revolution of the driving-wheel, and the contracted springs expand, the points of attachment are moved upward and at the 90 same time horizontally, and the treadle A and the lower end of the pitman are also moved in a horizontal direction, or in a reverse direction to their movement when the springs 95 were being compressed. The advantages resulting from these horizontal movements of the treadle consist largely in changing the 100

angle between the treadle and the pitman at the proper times to assist the upper end of the pitman to pass its dead-centers. It is also true that the vertical and horizontal yielding movement of the treadle prevents shocks and strains to the operator and relieves the limbs by permitting a constant change of position and straightening thereof, thus overcoming the cramping of the ankle-joints and other annoying and injurious effects resulting from a fixed or unyielding position or movement of the treadle. These advantages will be fully recognized and appreciated by those skilled in the art of treadle-power.

The drawings show the springs as pivotally attached to the treadle and fixedly secured to the rod D. It is evident, however, that this arrangement could easily be reversed and the springs be fixedly secured to the treadle and pivoted to the bar D or other part of the frame of the machine; also, that the springs could be fixedly secured to both the treadle and the rod D and the ends of this rod be journaled in the frame to give the required oscillation. This I regard as simply a mechanical change of arrangement without in any substantial particular departing from the principle of my invention.

I do not desire to limit my invention to the use of springs of any special construction or shape or to any special arrangement of the springs in relation to the treadle or the place or manner of their attachment thereto, or to other parts of the machine, further than that the treadle shall be pivoted so that it is free to rock or oscillate and shall be supported upon springs. The form of spring F shown in Fig. 3 of the drawings, which is a spirally-coiled spring slipped upon the rod D and secured thereto by a screw or other means and pivotally attached to the treadle, may be used to advantage. Many other forms of springs variously attached to the treadle and other parts of the machines can be employed to fulfill the conditions of my invention.

I am aware that there are descriptions of treadles supported upon the lower ends of vertically-suspended spirally-coiled springs. In such constructions the expansion and contraction of the springs carries the treadle only in a vertical direction and fails to accomplish one important result which I accomplish by my invention—viz., to give a horizontal or lateral movement to the treadle and the foot of the pitman attached thereto at the same time the treadle is oscillated to give the desired vertical throw to the pitman.

I am also aware of descriptions in which treadles have been supported upon springs attached near the heel part of the treadle or foot-sandals; but in these constructions the springs are rigidly, not pivotally, secured to the treadle and the treadle cannot be rocked or oscillated except as the springs are bent and compressed, and I fail to see how the necessary range of movement in the treadle to give the desired throw to the pitman can

be obtained without the intervention of other devices or the exertion of such force by the operator as would result in great fatigue and discomfort.

The advantage of spring-supported and pivotally-operating treadles as compared with those which are spring-supported but not pivoted, or those which are pivoted but not spring-supported, are obvious and important. In those which are simply spring-supported the springs must be compressed sufficiently to give the desired throw to the pitman, and this soon weakens or sets the springs or wearis the operator. By the use of spring-supported and pivotally-operating treadles the pitman can be attached directly to the treadle, and the range of vertical movement necessary to give the desired throw to the pitman is easily secured by rocking or oscillating the treadle upon the pivots without the application of force sufficient to weaken the springs or cause discomfort or fatigue to the operator. At the same time the springs, under the weight of the feet and limbs of the operator and the force naturally applied to oscillate the treadle, are brought into action sufficiently to give the desired horizontal or lateral movements to the treadle and its attached pitman and at the same time to reduce and distribute the shocks and strains and give the desired relief and comfort to the operator.

What is claimed as new is—

1. The combination of a treadle and spring-connections pivotally supporting the same from the frame of the machine, the springs being secured to the frame and to the treadle by fixed attachments at one of their ends and by pivotal attachments at their other ends, whereby the contraction and expansion of the springs will give to the treadle combined vertical and horizontal movements, as and for the purpose set forth.

2. The combination of a treadle and supporting-springs, the springs being pivotally secured at one of their ends to the treadle, while their opposite ends are fixed to the frame of the machine, whereby the contraction and expansion of the springs will give to the treadle combined vertical and horizontal movements, as and for the purpose set forth.

3. The combination of a treadle and supporting-springs, the springs being secured to the frame of the machine and to the treadle by fixed attachments at one of their ends and by pivotal attachments at their other ends, the points of attachment between the treadle and the springs being out of a vertical plane through the axes of the springs, whereby the contraction and expansion of the springs will move the treadle horizontally, as and for the purpose set forth.

FRANK B. JOHNSON.
